UNITED STATES PATENT OFFICE

118,713

DESIGN FOR A SUPPORT FOR OPHTHALMIC LENSES AND SPECTACLE MOUNTINGS OR SIMILAR ARTICLES

Edwin Reynolds, Vineland, N. J.

Application June 8, 1939, Serial No. 85,395

Term of patent 14 years

To all whom it may concern:

Be it known that I, Edwin Reynolds, a citizen of the United States, residing at Vineland, in the county of Cumberland and State of New Jersey, have invented a new, original, and ornamental Design for a Support for Ophthalmic Lenses and Spectacle Mountings or Similar Articles, of which the following is a specification, reference being had to the accompanying drawing, forming part thereof.

Figure 1 is a side perspective view of a support for ophthalmic lenses and spectacle mountings or similar articles, showing my new design; and Figure 2 is a top plan view; and Figure 3 is an end view thereof.

I claim:

The ornamental design for a support for ophthalmic lenses and spectacle mountings or similar articles, substantially as shown.

EDWIN REYNOLDS.
